DESIGN FOR A COMBINATION CARD HOLDER AND MEMORANDUM TRAY

Leo J. Seigenberg, Los Angeles, Calif.

Application April 2, 1940, Serial No. 91,417

Term of patent 7 years

To all whom it may concern:

Be it known that I, Leo J. Seigenberg, a citizen of the United States, residing at Los Angeles, in the county of Los Angeles, State of California, have invented a new, original, and ornamental Design for a Combination Card Holder and Memorandum Tray of which the following is a specification, reference being had to the accompanying drawing, forming part thereof.

I claim:

The ornamental design for a combination card holder and memorandum tray, as shown.

LEO J. SEIGENBERG.
